J. B. GRIMES.

PROCESS FOR MAKING ADHESIVE METAL, LETTERS, FIGURES, DESIGNS, &c.
APPLICATION FILED AUG. 24, 1914. RENEWED JULY 8, 1915.

1,151,519.

Patented Aug. 24, 1915.

UNITED STATES PATENT OFFICE.

JAMES B. GRIMES, OF DAYTON, OHIO, ASSIGNOR, BY MESNE ASSIGNMENTS, TO THE METAL LABEL & MANUFACTURING COMPANY, OF SPRINGFIELD, OHIO, A CORPORATION OF OHIO.

PROCESS FOR MAKING ADHESIVE METAL LETTERS, FIGURES, DESIGNS, &c.

1,151,519.

Specification of Letters Patent.

Patented Aug. 24, 1915.

Application filed August 24, 1914, Serial No. 858,414. Renewed July 3, 1915. Serial No. 38,784.

To all whom it may concern:

Be it known that I, JAMES B. GRIMES, a citizen of the United States, residing at Dayton, in the county of Montgomery and State of Ohio, have invented certain new and useful Improvements in Processes for Making Adhesive Metal Letters, Figures, Designs, &c.; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a process of making metallic letters, figures, designs, etc., for attachment to various articles such as leather, cloth or any surface where it is desirable to attach a label, marker or emblem. For example, hats, in such case the name or initials of the owner is embossed thereon, also perfumery bottles with any ornamental design embossed thereon together with the name of the firm or person, and to an almost endless variety of other uses. The material on which the letters, figures, designs, etc., are embossed consists of a thin metal ribbon or sheet and a non-metallic ribbon or sheet of paper having a suitable adhesive substance or surface. Both of these are united in one ribbon or sheet of material, the adhesive strip being united in the process of manufacture and, likewise, the embossing. It is well known that metallic surfaces will resist the application of glue or an adhesive substance to such an extent that it is impracticable to use a metallic ribbon alone in the manufacture of metal designs, letters, markers, etc. In endeavoring to manufacture such from a ribbon sheet metal, it has heretofore been the practice to secure the paper or non-metallic surface containing the adhesive directly to the metal surface. In order to do this the metal surface has to be first treated with an application of acid or a sand blast to impart thereto a certain degree of porosity to prepare it for the adherence of the non-metallic ribbon or sheet. This has been found to be objectionable owing to the tendency and liability of the two sheets or ribbons to separate. In order to avoid this,

my process consists in uniting the metallic and non-metallic ribbons into substantially one integral ribbon without relying upon the permanency of an intervening adhesive substance. To this end the two ribbons are united by a series of small clamping tongues 55 or prongs which are punched through the ribbons or sheets and bent over against the glue side of the same. These tongues are pressed or embedded into the adhesive side or the non-metallic surface to such an extent as to not interfere with attaching the finished product to such article to which it may be desired to unite it.

In order that my process may be clearly understood, I annex hereto illustrations showing the various steps in the process.

Of these illustrations, Figure 1 is a view of the various punches and dies shown in section on the line 2—2 of Fig. 2; Fig. 2 is a plan view of the sheet or strip showing the various stages of the process of manufacture; and Fig. 3 is a plan view of the finished article when stamped from the sheet constituting the metallic sheet and the adhesive sheet when united.

Referring in detail to the drawings, 1 and 2 designate respectively rolls of sheet metal or ribbon, and paper ribbon or other similar or non-metallic material one side of which has been previously treated with a substantial surface of adhesive substance such as glue. These two sheets or ribbons are passed through suitable guide rollers 3—3 in contact with each other as shown at 4, the metal ribbon 1 being above and the adhesive ribbon 2 below with the glued surface thereof lowermost.

A designates a holder in which are set a suitable number of tongues 6 therein.

Below the punches in the holder A, a female member B is located having a number of apertures 7 corresponding to the number of punches 5 and into which they enter in the operation. The punches 5 in passing through the ribbon or sheet 4 form the tongues 6 which stand downwardly substantially at right angles to the ribbon. After this operation of punching, the ribbon 4 is passed forwardly to a set of dies which are formed in the adjacent surface of the members C and D. The coöperating surfaces of these members C and D are such as to give the tongues 6 a uniformly inward bend

which is due to the curved surface 8 of the female die member D. The ribbon 4 is at this time prepared for the final operation of permanently uniting the two ribbons consisting of clamping the tongues 6 into the glued surface and embossing. This operation is performed by the die members E and F, the coöperating surfaces of which are prepared with the necessary design, 10 letters or marks, to be embossed on the strip or sheet 4, and with the necessary surface to securely bend the tongues 6 against the underside of the ribbon 4. The final operation consists in cutting the article 15 from the ribbon 4 which has thus previously been prepared. This operation is done by a suitable punch and die G and H. It will be understood that all of these operations take place at one and the same time after 20 the prepared ribbon 4 has been advanced.

The adhesive side of the finished product is shown in Fig. 3. It will be observed that the tongues 6 are there shown to be bent against the glued surface of the article. 25 The prepared ribbon, as shown in Fig. 2, illustrates the several steps of the process. In the first two sections on the left hand end thereof the two initial positions of the tongues are shown. In the third section, 30 the work of embossing and clamping the tongues against the glued surface of the ribbon 4 is shown, while in the last position, the opening is shown which is left by the punches which form said tongues and the 35 finished article by cutting it from said ribbon. It is possible to punch the tongues 6 and deflect them sufficiently for the subsequent clamping operation in a single operation, therefore, the entire process may 40 consist in three distinct operations instead of four as described. The metal surface on

which the design, letters, or other impression is formed may be treated in any of the well known ways to give it the desired finish or luster. This, however, does not constitute a feature of my process. 45

Having described my invention, I claim:

1. The herein described process of making metallic markers and designs, which consists in bringing together a metallic ribbon or sheet and a non-metallic ribbon or sheet, one side of the latter being coated with an adhesive, and the non-adhesive side thereof being adjacent to the metallic ribbon, in punching in the two ribbons thus brought in contact, a suitable number of tongues, in clamping said tongues to unite said two ribbons or sheets and embossing the same, and in cutting out the said united and embossed portions of said ribbon. 50

2. The process of making metallic markers and the like for attachment to articles to be designated thereby which consists in bringing together a metallic ribbon or sheet and a non-metallic ribbon or sheet, the latter having one side thereof applied with an adhesive substance, in cutting a series of uniting members in said ribbon after being brought together, in bending inwardly said uniting members from the position in which they were left when punched, in clamping said uniting members against the adhesive side of the non-metallic ribbon or sheet, and embossing the same, and in cutting from said ribbons the portion united and embossed. 55

In testimony whereof I affix my signature, in presence of two witnesses.

JAMES B. GRIMES.

Witnesses:

EDWARD A. WEAVER,
MELLIE GALLOWAY.
